DISH WASHING DEVICE**Katherine B. Anderson, Vancouver, British Columbia, Canada**

Application February 11, 1953, Serial No. 336,427

Claims priority, application Canada August 25, 1952

5 Claims. (Cl. 299—83)

This invention relates to a device for assisting in the washing of articles, such as dishes, baby-bibs, place mats, vegetables, fowl, and the like.

An object of the present invention is the provision of a device which makes it possible to wash articles, such as dishes or the like, quickly and easily without the necessity of placing them in a container of water.

Another object is the provision of a device of the nature described which may be mounted on or near taps already installed, or may be constructed as part of a plumbing fixture.

At the present time, most dishes are washed by placing them in a pan or sink of hot water. The trend is to place the dishes after washing on racks and to rinse them by spraying them with hot water. The main objection to washing dishes ordinarily is that the housewife has to put her hands in the hot soapy washing water.

The present device makes it possible to wash the dishes without placing them in a container of water and without the necessity of an extra rinsing operation. The device includes a container for holding a cleansing agent and through which water may run, and means for supporting the container near and in line with the outlet of a tap. It is desirable to provide for relative movement between the container and the tap outlet. The container may be so mounted that it may be moved into and out of line with the tap outlet, or the container may be stationary and the outlet movable. The latter is very simple with taps of the type having swingable spouts.

A dish may be washed by holding it in the water passing through the container after the latter has been in contact with the cleansing agent. The dish is easily rinsed by moving the container away from the tap outlet, or by moving the latter away from the container.

Examples of this invention are illustrated in the accompanying drawings, in which,

Figure 1 is a front elevation of one form of dish washing device supported by a pair of taps having a common discharge spout,

Figure 2 is a plan view of the device and its mounting,

Figure 3 is a sectional view taken substantially on the line 3—3 of Figure 2,

Figure 4 is a side elevation of an alternative form of the invention,

Figure 5 is a side elevation of still another form of the invention, and

Figure 6 is an enlarged section taken on the line 6—6 of Figure 5.

Referring to Figures 1 to 3 of the drawings, 10 and 11 are hot and cold water taps having a common spout 12 with an outlet end 13. A container 16 is mounted in line with the discharge 13 of the taps. This container may be made out of any suitable material as long as it is capable of holding a cleansing agent, such as soap, soap powder or a detergent, and as long as water may run through it. Suitable screens may be provided for regulating the consumption of the cleansing agent or, as shown,

2

the container may be formed of wire screening. The size of the openings in the screening determines the rate of consumption of the cleansing agent. The container may have a perforated or screen cover 17 mounted thereon by means of a hinge 18.

The container is mounted on one end of an arm 20, and this arm is preferably, but not necessarily, extensible. One way of making it extensible is to form the arm of telescopic parts 21 and 22, the latter slidably fitting into the former, see Figure 3. The opposite end of the arm is supported so that the container may be positioned beneath the tap outlet, and a suitable mount is provided for this purpose. The mount may be connected to a wall or, as shown, it may be supported by the taps. In this form of the invention, the mount consists of a plate 25 slidably mounted on a horizontal bar 26 which is provided with hooks 27 at its opposite ends adapted to fit over portions of the taps 10 and 11 or the water pipes 29 extending thereto. In the latter case, the hooks fit over the water pipes between the taps and the wall 30 from which the taps project.

It is desirable to be able to adjust the arm 20 vertically, and if the spout 12 is stationary, the arm should be swingably mounted on the plate 25. One way of accomplishing this is to provide the plate with a vertical rod 33 spaced outwardly from the face thereof, see Figure 3, which extends freely through a hole in the part 21 of the supporting arm 20. Collars 34 and 35 above and below the arm may be tightened on to the rod by means of set screws 36 and 37 to retain the arm in any adjusted position on the rod while permitting said arm to swing in a horizontal plane.

With the mount illustrated in Figures 1 to 3, the container may be mounted on taps of different types and sizes. The plate 25 may be shifted laterally on the bar 26 and the arm 20 adjusted so that the container 16 may be moved beneath the outlet 13 of the taps.

After a suitable cleansing agent is placed in the container 16, it is a very simple matter to wash dishes beneath the tap outlet. Water from the outlet passing through the container comes into contact with the cleansing agent and carries some of the latter with it. A dish may be washed by holding it in the water pouring from the container and wiping it with a mop, brush or cloth. When it is desired to rinse the dish, it is only necessary to move the container clear of the tap outlet. Thus, the dish may be quickly and easily washed and rinsed. The container is moved to one side clear of the tap spout when it is not needed.

If the spout 12 may be swung laterally, the container may be rigidly mounted in position. In this case, when it is desired to rinse the dish, the spout may be swung clear of the container.

Figure 4 illustrates a container 16 mounted beneath the outlet 40 of a single tap 41. The container is supported by an extensible arm 20 which is adjustably and swingably mounted on the vertical rod 33. This rod, however, is carried by a supporting plate 44 which is suspended from the tap or the pipe connected thereto. This plate is mounted on the tap or the pipe in the same manner as one of the ends of the supporting bar 26 of Figures 1 to 3.

Figure 5 shows a container 16 mounted on a modern tap or spout 47 having an outlet 48. In this example, the outer end of each of the parts 21a and 22a of arm 20a is bent so that the main portion of the arm lies in an inclined plane. The outer end of the part 21a is swingably mounted on a pin 50 carried by a clamp 51 secured to the tap or spout 47. This clamp is tightened by means of a nut and bolt at 52.

The dish washing device of each illustrated form of the invention is used in the same manner. The container sprays water containing a cleansing agent over dishes held

beneath it. Each dish may be held near the edge thereof so that it is not necessary to get the hands in the hot water. The rinsing operation is done by moving the container out of the water.

While each illustrated form of the invention includes means for supporting the container from a tap or pipe leading thereto, it is obvious that the mount for the container may be connected directly to the wall from which the tap projects. Furthermore, it would not be difficult permanently or removably to attach the containers to tap fixtures during the manufacture thereof.

What I claim as my invention is:

1. A device for assisting in the washing of articles, such as dishes or the like, under a water tap, comprising a vertical mounting plate to be suspended from a tap or a pipe leading thereto, a vertical rod supported by and spaced outwardly from the plate, an arm slidably and swingably mounted at one end on the rod, means for positioning the arm on the rod without interfering with the swinging action thereof, and a container for holding a cleansing agent and through which water may run connected to the opposite end of the arm, said container being moved into and out of line with the outlet of said tap when the arm is swung on the vertical rod, whereby articles may be washed when held in water passing through the container after being in contact with the cleansing agent therein.

2. A device for assisting in the washing of articles, such as dishes or the like, under a water tap, comprising a vertical mounting plate to be suspended from a tap or a pipe leading thereto, a vertical rod supported by and spaced outwardly from the plate, an extensible arm slidably and swingably mounted at one end on the rod, means for positioning the arm on the rod without interfering with the swinging action thereof, and a container for holding a cleansing agent and through which water may run connected to the opposite end of the arm, said container being positioned beneath the outlet of said tap by adjusting the arm on the rod and the length of said arm, and said container being moved with and out of line with the outlet of said tap when the arm is swung on the vertical rod, whereby articles may be washed when held in water passing through the container after being in contact with the cleansing agent therein.

3. A device for assisting in the washing of articles comprising a bar having hooks at its opposite ends adapted to fit over portions of spaced hot and cold water taps

having a common outlet, a plate slidably mounted on the bar, an arm mounted at one end for vertical adjustment on the plate, and a container for holding a cleansing agent and through which water may run connected to the opposite end of the arm, said container being movable into and out of line with said outlet, whereby articles may be washed when held in water passing through the container after being in contact with the cleansing agent therein.

4. A device for assisting in the washing of articles comprising a bar having hooks at its opposite ends adapted to fit over portions of spaced hot and cold water taps having a common outlet, a plate slidably mounted on the bar, a vertical rod supported by and spaced outwardly from the plate, an arm slidably and swingably mounted at one end on the rod, means for positioning the arm on the rod without interfering with the swinging action thereof, and a container for holding a cleansing agent and through which water may run connected to the opposite end of the arm, said container being moved into and out of line with the outlet of said tap when the arm is swung on the vertical rod, whereby articles may be washed when held in water passing through the container after being in contact with the cleansing agent therein.

5. A device for assisting in the washing of articles comprising a bar having hooks at its opposite ends adapted to fit over portions of spaced hot and cold water taps having a common outlet, a plate slidably mounted on the bar, a vertical rod supported by and spaced outwardly from the plate, an extensible arm slidably and swingably mounted at one end on the rod, a collar slidable on the rod beneath the arm, a set screw in the collar for securing the latter to the rod, and a container for holding a cleansing agent and through which water may run connected to the opposite end of the arm, said container being moved into and out of line with the outlet of said tap when the arm is swung on the vertical rod, whereby articles may be washed when held in water passing through the container after being in contact with the cleansing agent therein.
